UNITED STATES PATENT OFFICE.

ADOLPH B. JOHNSON, OF DES MOINES, IOWA.

DESIGN FOR A KITCHEN-CABINET.

SPECIFICATION forming part of Design No. 30,398, dated March 28, 1899.

Application filed February 8, 1899. Serial No. 704,744. Term of patent 14 years.

To all whom it may concern:

Be it known that I, ADOLPH B. JOHNSON, a citizen of the United States, residing at Des Moines, in the county of Polk and State of Iowa, have invented and produced a new and original Design for a Kitchen-Cabinet, of which the following is a specification, reference being had to the accompanying perspective view and drawing, forming part thereof, and in which—

The letter A designates the lower portion of the cabinet. It has a door B at each end leading to a chamber that extends from end to end in the rear part of the said lower extension.

C is a top on the lower portion A, and C² is an extension of said top and is supported upon a bracket D on the end wall of the lower portion A.

f, f', and f'' are drawers fitted in the front part of the lower portion A in parallel position with the one end wall, and f''' is a drawer aside of the lower drawer f'', and the interior space in the front of the lower portion A and above the drawer is adapted for locating a flour-sifter therein under the top C.

A² is the top portion of the cabinet fitted on the rear part of the lower portion A.

g and g' are mating drawers in the center of the lower part of the upper portion A², and four smaller drawers of uniform size and shape are located in the square corners at the ends of those two mating drawers.

H is a drawer that extends from one end wall of the top portion A² to the other end and is located immediately above the drawer g.

J and J² are mating doors hinged to the end walls of the upper portion A², and K and K² are fixed shelves that extend from one end wall to the other.

L is an ornamental verge-board fixed on the front edge of the top portion A², and m is a molding fixed at the base of said board and extending around the corners at the tops of the end walls.

Having thus described my invention, what I therefore claim, and desire to secure by Letters Patent, is—

The design for a kitchen-cabinet as herein shown and described.

ADOLPH B. JOHNSON.
